CAR-ROOF FRAME.

1,084,128.

Specification of Letters Patent.

Patented Jan. 13, 1914.

Application filed January 15, 1912. Serial No. 671,301.

To all whom it may concern:

Be it known that we, WILLIAM S. BIDLE and JOSEPH A. COSTELLO, citizens of the United States of America, residing at Cleveland, in the county of Cuyahoga, State of Ohio, have invented certain new and useful Improvements in Car-Roof Frames; and we do hereby declare the following to be a full, clear, and exact description of the invention, such as will enable others skilled in the art to which it pertains to make and use the same.

This invention relates to improvements in car-roof-frames, and pertains more especially to improvements in car-roof construction for a railway box-car.

One object of this invention is to connect together the two side plates of the frame of a car-roof by a carline which comprises a body which is trough-shaped in cross-section and extends from over each side plate to and over the other side plate, to have each end-portion of the carline in the form of an angle-plate which is integral with said body and has one wing thereof arranged substantially horizontally and resting on the adjacent side plate and has its other wing depending at and overlapping the outer side of said side plate, to have the said body reinforced by two laterally and outwardly projecting flanges which are arranged at opposite sides respectively and extend longitudinally of said body and have their end-portions sloping downwardly toward and terminating in the angle-plate-forming end-members of the carline, to have said sloping portions of said flanges gradually enlarged in width toward said angle-plate-forming members, and to have said angle-plate-forming members extending longitudinally of the side plates as far as said sloping portions of said flanges project from the aforesaid body of the carline, so that the carline is particularly strong and durable at the junction of said body with said angle-plate-forming members and has a comparatively large seat on each side plate without necessitating recessing or otherwise weakening or materially mutilating the side plates.

Another object is to provide said carline on top with metal plates which extend transversely of the carline and rest on the flanges of the body of the carline and to have said plates forming seats for the ridge-pole and

purlins of the car-roof-frame and thereby avoid the necessity of recessing or depressing the carline at said flanges to form seats for the purlins and ridge-pole.

Another object is to attach the ridge-pole-seating plate and the purlin-seating plates to the flanges of the carline, and to provide each plate with two upwardly projecting flanges extending transversely of the carline and overlapping opposite sides respectively of and forming side abutments for the ridge-pole or purlin seated on said plate.

Another object is to have the ridge-pole-seating plate, and each purlin-seating plate provided at the under side of its bottom with a rib which projects into the body of the carline between the flanges of the said body and positively prevents displacement of said plate transversely of the carline upon the application of said plate to the carline before and during the attachment of the plate to the carline.

Another object is to have each flange of the ridge-pole-seating plate and each flange of each purlin-seating plate provided externally with a rib which is arranged centrally between the flanges of the body of the carline, and to have said rib of each plate terminating in or contiguous to the rib at the under side of the bottom of the plate so as to materially reinforce the plate centrally between the ends of the flanges of the plate.

Another object is to prevent shearing of the bolts employed in securing the purlins and ridge-pole to the carline by any force tending to displace the ridge-pole and purlins endwise or laterally.

With these objects in view, and to the end of attaining any other advantage hereinafter appearing, this invention consists in certain features of construction, and combinations and arrangement of parts, hereinafter described, pointed out in the claims, and illustrated in the accompanying drawings.

In said drawings, Figure 1 is a top plan of a portion of a car-roof-frame embodying our invention. Figs. 2 and 3 are vertical sections on line 2—2, and line 3—3, respectively, Fig. 1. Fig. 4 is a vertical section on line 4—4, Fig. 3, looking outwardly. Fig. 5 is a central vertical section on line 5—5, Fig. 2. Figs. 6 and 7 are vertical sections on line 6—6 and line 7—7, respectively, Fig. 1. Fig. 8 is a horizontal sec-

tion on line 8—8, Fig. 2, looking downwardly. Fig. 9 is a section on line 9—9, Fig. 2, looking outwardly. Fig. 10 is a section on line 10—10, Fig. 2, looking downwardly. Figs. 11 and 12 are vertical sections on line 11—11 and line 12—12, respectively, Fig. 1. Figures from 3 to 12 inclusive are drawn on a larger scale than Figs. 1 and 2.

10 Referring to Figs. 1 and 2 of the drawings, A and A indicate the two laterally spaced metal side plates of a car-roof-frame embodying our invention. Said side plates are applied in any approved manner and 15 extend longitudinally of the car-roof-frame. Said side plates are arranged substantially horizontally and parallel. Each side plate A is provided at the top thereof (see Figs. 1, 2, 3, 4, 5, and 9) with a laterally and 20 inwardly projecting substantially horizontally arranged flange a which extends longitudinally of said side plate, and said side plate (see Figs. 1, 2 and 3) is shown provided at the bottom with a laterally and 25 outwardly projecting flange 13. The side plates A and A are connected together by any suitable number of carlines and are shown connected together in Figs. 1 and 2 by a metal carline which comprises a 30 trough B which (see Figs. 4, 5 and 9) extends between and over the flanges a of the side plates but only about half way across said flanges. Said trough is U-shaped in 35 cross-section and (see Fig. 2) slopes at the top thereof upwardly toward a point centrally between the ends of the carline. Said trough is provided at the top and externally with two laterally and outwardly projecting flanges b and b arranged at opposite 40 sides respectively and extending longitudinally of the trough and sloping upwardly in the direction of the central portion of the carline. Said trough is provided at each end with a horizontally arranged plate 45 15 which is integral with the bottom of the trough and (see Figs. 1, 2 and 3) forms an extension of said bottom and rests on the flange a of the adjacent side plate. Said plate 15 is provided with a downwardly 50 projecting flange 16 which overlaps the outer side of the adjacent side plate and is riveted, as at 17, or otherwise secured to said side plate. The flanges b and b of the carline preferably extend from end to end 55 of the trough B and consequently over the side plates A, and each end-portion of each of said flanges (see Figs. 2 and 3) slopes, as at 18, quite abruptly downwardly toward and terminates in the adjacent plate 15. 60 Each sloping end-portion 18 of each flange b (see Figs. 1, 4 and 9) is preferably gradually enlarged in width toward the adjacent plate 15, and said plate extends longitudinally of the adjacent side plate A as 65 far as the adjacent sloping end-portions of

the flanges b project laterally of the trough B so that the carline is particularly strong and durable at the junction of said trough with said plate and has a comparatively large seat on each side plate without necessitating recessing or otherwise weakening or materially mutilating the side plates. 70

We would here remark that the hereinbefore described construction and application of the carline permits the greatest possible head-room below the carline, and the trough of the carline permits the passage of air longitudinally of and through the carline from end to end of the carline so as to ventilate the carline internally. 75

Figs. 1, 2, 3, 6, 7, and 8 illustrate the application of a ridge-pole C to the carline. The ridge-pole C constitutes the central longitudinal member of the car-roof frame and is parallel with and arranged centrally between the side plates A and extends across the top of the carline and of course across the top of the flanges b of the carline. A metal plate D is interposed between the bottom of the ridge-pole and the top of the carline. The plate D is arranged substantially horizontally and extends transversely of the carline, being seated on the flanges b and b of the carline centrally between the ends of the carline. The plate D is provided with two upwardly projecting flanges d and d arranged at and overlapping opposite sides respectively of and forming side abutments for the ridge-pole. Two bolts E are instrumental in attaching the ridge-pole to opposite flanges b respectively of the carline. Said bolts are arranged vertically centrally between the flanges d and d of the plate D and (see Figs. 5, 6, 7, and 8) extend from within the ridge-pole through bolt-holes 20 formed in the said plate and through bolt-holes 21 which are formed in the flanges b of the carline and register with said bolt-holes in said plate. Nuts e are applied to the bolts 100 E at the under sides of said flanges b. 110

The plates D (see Figs. 5, 7 and 8) is provided at its under side and centrally between its ends with a rib 22 which projects downwardly into the trough B of the carline and extends transversely of said plate and consequently longitudinally of the carline. Said rib 22 prevents displacement of the plate D laterally of the carline upon the application of said plate to the carline. 115 120

Each flange d of the plate D (see Figs. 1, 2, 7, and 8) is provided externally of and centrally between its ends with a laterally and outwardly projecting rib 23 which extends up and down said flange. The ribs 125 23 materially reinforce the flanges d and are preferably arranged contiguous to the bottom rib 22 of the plate D so that said ribs 22 and 23 materially strengthen said plate. 130

The plate D (see Figs. 6 and 8) is provided between one of the bolts E and one of the flanges d of said plate with a downwardly projecting lug 25, and between the other bolt E and the other flange d has a downwardly projecting lug 26, as shown in Figs. 7 and 8. The lugs 25 and 26 are preferably struck downwardly from the plate D preparatory to the application of the plate to the carline. Said lugs project downwardly through and snugly engage holes 27 formed in the flanges b of the carline, as shown in Figs. 6 and 7, and have their lower portions clenched, as at 28, at the under sides of said flanges so as to attach said plate to said flanges and consequently to the carline. By the projection of the bottom rib 22 of the plate D into the trough B of the carline and by the attachment of said plate to the flanges b of the carline through the medium of the lugs 25 and 26 said plate is so firmly secured to the carline that such a displacement of the plate independently of the carline as would tend to shear the bolts E is impossible.

Figs. 1, 2, 9, 10, 11, and 12 illustrate the application of the purlins G to the carline. Between the ridge-pole C and each side plate A are shown arranged two purlins G which extend across the top of the carline and of course across the tops of the flanges b of the carline, which purlins constitute longitudinal members of the car-roof-frame are spaced longitudinally of the carline. A metal plate H is interposed between the bottom of each purlin and the top of the carline, which plate extends transversely of the carline and is seated on the flanges b and b of the carline and forms a seat for the purlin mounted on said plate. Each purlin-seating plate H is provided with two upwardly projecting flanges h and h arranged at opposite sides respectively of the purlin mounted on said plate, and said flanges form side abutments for said purlin. Two bolts I are instrumental in attaching each purlin G to opposite flanges b respectively of the carline and are arranged vertically centrally between said flanges and (see Figs. 9, 10, 11, and 12) extend from within said purlin through bolt-holes 30 formed in said plate and through bolt-holes 31 formed in the flanges b of the carline and registering with said bolt-holes in said plate. Nuts J are applied to the bolts I at the under sides of the flanges b. Each purlin-seating plate H (see Figs. 9, 10, and 11) is provided at its under side and centrally between its ends with a rib 32 which projects downwardly into the trough B of the carline and extends transversely of said plate and consequently longitudinally of the carline, which rib prevents displacement of said plate laterally of the carline upon the application of said plate to the carline.

Each flange h of each plate H (see Figs. 10 and 11) is provided externally and centrally between its ends with a laterally and outwardly projecting rib 33 which extends up and down said flange, which ribs materially reinforce said flanges and are preferably arranged contiguous to the bottom rib 32 of said plate so that said ribs 32 and 33 materially strengthen said plate.

Each plate H (see Figs. 10 and 12) is provided between one of the bolts I extending through said plate and one of the flanges h of said plate with a downwardly projecting lug 35, and between the other bolt I extending through said plate and the other flange h of said plate has a downwardly projecting lug 36 as shown in Figs. 10 and 11. The lugs 35 and 36 of each plate H are preferably struck downwardly from said plate preparatory to the application of the plate to the carline. The lugs 35 and 36 of each plate H project downwardly through and snugly engage holes 37 formed in the flanges b of the carline, as shown in Figs. 11 and 12, and have their lower portions clenched, as at 38, at the under sides of said flanges so as to attach said plate to said flanges and consequently to the carline. By the projection of the bottom rib 32 of each plate H into the trough B of the carline and by the attachment of said plate to the flanges b of the carline through the medium of the lugs 35 and 36 said plate is so firmly secured to the carline that such a displacement of said plate independently of the carline as would tend to shear the bolts I extending through said plate is positively prevented.

It will be observed that a car-roof-frame comprising the construction hereinbefore described is strong and durable and permits the greatest possible head-room below each carline of the car-roof-frame, that said carline comprises a trough extending between and over the laterally spaced side plates of the car-roof-frame, that said carline is rendered particularly strong and durable over said side plates and at the same time is provided with large seats on said side plates, that each purlin or longitudinal member of the car-roof-frame is seated on said carline through the medium of a metal plate interposed between said carline and said longitudinal member, and that said last-mentioned plate is provided with a rib which is inverted-arch-shaped in cross-section, as shown in Fig. 9, and depends into and extends longitudinally of the trough of said carline and not only reinforces said plate but has opposite sides thereof in contact with opposite sides respectively of the carline-trough so as to positively prevent displacement of said plate laterally of the carline upon the application of said plate to the carline.

What we claim is:—

1. In a car-roof-frame, the combination, with the two laterally spaced side plates, of a metal carline comprising a trough which 5 extends between and over the side plates and is provided at each end with a plate which lies on the adjacent side plate and forms an extension of the bottom of the trough and is provided with a flange overlapping the 10 outer side of and secured to said side plate, said trough being provided at the top and externally with laterally and outwardly projecting flanges extending longitudinally of the trough and over the side plates, each 15 end-portion of each flange sloping downwardly over the adjacent side plate toward and terminating in the adjacent bottom-extension-forming plate of the trough.

2. In a car-roof-frame, the combination, 20 with a suitably supported metal carline comprising a trough which constitutes a transverse member of the car-roof-frame and is provided at the top with laterally and outwardly projecting flanges extending longitudinally of the trough, and a longitudinal member of the car-roof-frame, said longitudinal member being arranged over and extending across said flanges, of a metal plate interposed between said longitudinal member 25 and said flanges, which plate is attached to said flanges and has upwardly projecting flanges at the sides of said longitudinal member, said plate being provided with a downwardly projecting rib which is inverted- 30

35 arch-shaped in cross-section and arranged within and longitudinally of the aforesaid trough, said rib having opposite sides thereof in contact with opposite sides respectively of said trough.

3. In a car-roof-frame, the combination, 40 with a suitably supported metal carline comprising a trough which constitutes a transverse member of the car-roof-frame and is provided at the top with laterally and outwardly projecting flanges extending longitudinally of the trough; a longitudinal member of the car-roof-frame, said longitudinal member being arranged over and extending across said flanges, and bolts and nuts securing said longitudinal member to said 45 flanges, of a metal plate interposed between said longitudinal member and said flanges, which plate is provided with a downwardly projecting rib which is inverted-arch-shaped 50 in cross-section, said rib depending into and being arranged longitudinally of the aforesaid trough and in contact at its sides with the sides of said trough, the aforesaid plate being secured to the aforesaid flanges independently of the aforesaid longitudinal 55 member.

Signed by us at Cleveland, Ohio, this 30th day of December, 1911.
